UNITED STATES PATENT OFFICE.

ERNEST ROBERT SWANSON, OF CRANSTON, RHODE ISLAND, ASSIGNOR TO UNIVERSAL WINDING COMPANY, OF BOSTON, MASSACHUSETTS, A CORPORATION OF MASSACHUSETTS.

TENSION DEVICE.

Application filed October 11, 1926. Serial No. 140,969.

This invention relates to improvements in tension-devices for use with winding machines and other textile apparatus.

A particular object of the invention is to provide a tension-device having means for automatically threading the strand of yarn, thread or other filament into operative position in the device.

Another object of the invention is to provide a tension-device in which the operating parts are shielded and protected from lint, dirt and dust while yet being convenient of access for adjustment or cleaning.

Another object of the invention is to provide a tension-device which is generally more efficient in use for the purpose intended.

A preferred embodiment of the invention is described in the following specification and illustrated by the accompanying drawings in which:

Fig. 1 is an end elevation of a portion of a winding machine showing the present improved tension-device applied to use therewith;

Fig. 2 is a plan view of the same illustrating only the essential elements of the winding mechanism;

Fig. 3 is an enlarged side view of the tension-device looking in the direction indicated by the arrow in Fig. 2;

Fig. 4 is a similar view looking in the opposite direction; and

Fig. 5 is a view similar to Fig. 3 showing the strand-guiding parts of the device thrown back to provide access to the operating parts of the tension mechanism.

Referring first to Figs. 1 and 2 of the drawings, these views illustrate a conventional type of friction or drum-driven winding machine in which the cop, cone or package of yarn or other material is wound on a mandrel 2 and rotated through frictional contact with a driving-drum 3. The strand *y* of yarn or other material is traversed longitudinally of the mandrel 2 by means of a reciprocating thread-guide 4 carried on a horizontal traverse-bar or rod 5. The thread-guide 4 is provided with an eye or slot 6 through which the strand *y* leads to the cop or package, and a stud or roller 8 carried at the bottom of the guide is engaged with a helical groove formed in the periphery of a cylindrical cam 9. Through this

latter connection the rotation of the cam 9 causes reciprocation of the thread-guide 4 to traverse the strand *y* from one end of the mandrel 2 to the other to lay the yarn thereon in helical coils in the manner as well known to those versed in the art. The essential parts of the winding mechanism are herein illustrated merely to show the manner in which the tension-device, which forms the subject-matter of this application, functions in connection therewith. The parts of the winding mechanism are not herein described or shown in detail as they form no part of the present invention.

The present improved tension-device may be mounted on a suitable bracket 10 which, as herein illustrated, comprises an arm 11 fastened to a portion of the main frame 12 of the winding machine by means of bolts or screws 13. The bracket 10 is provided with a horizontal shelf or ledge 15 projecting from the end of the arm 11 and forming the support for a vertical pin or spindle 16 on which the tension-members are mounted. As illustrated in Figs. 3 to 5, the top of the shelf or ledge 15 is formed with a circular boss 17 and the pin 16 is driven into a hole located at the center thereof. Surrounding the pin 16 is a saucer-shaped, sheet-metal lint-guard 18 which seats against the top of the boss 17 and is held fixedly in place thereon by a shoulder 19 on the pin. The flaring peripheral rim of the lint-guard 18 projects upwardly within the outer downturned rim of the lower tension-disk 21 with a slight clearance therebetween. Slidable on the enlarged upper portion of the pin 16 are a pair of tension-disks 20 and 21 constructed with a contour of concavo-convex shape in cross-section. Preferably, the tension-disks 20 and 21 have flaring peripheral rims and their opposed faces are concaved at the center to provide a space therebetween when the convexed outer portions of the disks are in contact as illustrated in the drawings. It will be observed that the tension-disks 20 and 21 are placed on the pin 16 in opposite relation to each other to adapt their convex surfaces to bear on the strand of yarn or thread drawing therebetween, and suitable means are provided for pressing the disks together to cause them to resist the passage of the strand, whereby to apply tension thereto.

As herein shown the tension-disks are pressed together by means of one or more weights 22 supported on a sleeve or holder 23 which slides on the pin 16, the holder 5 being provided with a shoulder or abutment 24 at its lower end upon which the weights 22 rest. A helical spring 25 encircling the pin 16 is interposed between the sliding weight-holder 23 and the upper tension-disk 10 20. The spring 25 acts as a buffer or shock-absorber to permit the upper tension-disk to rise away from the lower disk when knots or enlargements pass through the device without overcoming the inertia of the 15 weights 22. The upper end of the pin or spindle 16 is reduced in diameter at 26 to adapt it to receive a hub or bearing 27 forming the support for a cylindrical shroud or hood 28 which is supported thereby to cover 20 the operating parts of the device. The hood or shroud 28 encloses the tension-weights 22, weight-holder 23, spring 25 and a portion of the upper tension-disk 20, its lower edge being spaced slightly above the bottom face of 25 the disk 20 so that it will not interfere with the passage of the strand between the disks.

Referring particularly to Figs. 1 and 2 of the drawings, the shelf or ledge 15 of the bracket 10 is extended forwardly at the front 30 of the tension-device where the strand y leads thereinto and is formed with a relatively narrow slit or reentrant threadway 29 through which the strand draws as it feeds to the tension-disks. Referring particularly 35 to Fig. 2, the shelf 15 reaches outwardly in two opposite prongs or fingers 30 and 31, between which is the threadway 29, with the end of the fingers flaring away from the throat of the slit to provide an opening or 40 entrance thereto. One of the fingers 31 is extended upwardly in an arm 33 which crooks around in an inclined portion 34. The arm 33 forms one part of the improved 45 strand-guiding means in the manner and for the purpose as hereinafter more fully explained.

At one side of the tension-bracket 10 is a vertical post 35 which forms the support for a second movable guiding-member 36. The 50 member 36 comprises a horizontal arm or rim 37 which is of semi-circular shape in plan view, see Fig. 2, to adapt it to partly encompass the tension-disks and their protecting hood 28 in spaced relation therewith. The arm 37 extends from a yoke-shaped member 38 which straddles the top of the post 35 and is pivoted thereto by means of 55 a cross-pin 39. Projecting upwardly from the hinge-member 38 is a finger 40 formed with a right-angled portion 41 at its upper end which projects across the top of the tension-pin or spindle 16 and normally rests thereon. The extension 41 of the finger 40 thus functions to hold the rim 37 of the 60 guiding-member 36 in horizontal position

slightly raised above the top of the shelf 15. Projecting upwardly from the rim 37 is a curved, sickle-shaped finger 44 which extends in the opposite direction from that of the crooked portion 34 of the arm 33, slightly 70 spaced rearwardly therefrom. The crook 34 and the curved finger 44 are arranged in this crossing relation to adapt the strand y to be drawn into the crotch formed therebetween, whereby it will be directed downwardly in under the rim 37 and carried into position between the two tension-disks 20 and 21 in the manner as hereinafter more 75 fully explained.

The main horizontal arm or rim 37 of the member 36 extends to the rear of the tension-device in a rectangular portion 45 which is joined to the hinge 38 at 46. This portion 45 of the rim 37 is offset at 47, see Fig. 2, to provide a recessed bearing 48 for the attachment of a slug-catcher or yarn-cleaner comprising two blades 50 and 51, see Fig. 4. The two blades 50 and 51 are attached to the bearing 48 by means of a screw 52 which reaches through from the rear of the bearing 48 and is threaded into an overlying plate 53 riveted to the front of the blade 50, see Fig. 4. The blades 50 and 51 extend in horizontal position with their adjacent working edges 54, 55 spaced slightly apart as shown 90 in Fig. 4. The opening between the working faces of the blades thus extends parallel with and in alinement with the contacting faces of the tension-disks 20, 21 so that as the strand y feeds through the tension-device it will draw through the slit or opening between the slug-catcher blades. Therefore, as the thread-guide 4 of the winding mechanism reciprocates back and forth longitudinally of the cop or package 100 being wound the strand y will play back and forth in the slit or opening between the blades 50 and 51 to scrape off slugs, bunches, dirt and other impurities adhering to the 105 yarn. Preferably, the blades 50 and 51 are made adjustable one in relation to the other 110 to vary the width of the opening between their working faces in accordance with the size or thickness of the yarn being operated upon. Conveniently, the lower blade 51 may have an enlarged hole 57 for the screw 52 to adapt it to be slid in relation to the upper blade 50. As shown in Fig. 2, the supporting parts of the blades 50 and 51 are fitted to a vertical slot 58 in the bearing 48 to maintain them in proper alinement in whatever position they may be adjusted.

Having now described a preferred form and construction of the invention, its method of operation will next be explained. The strand y of yarn, thread or other attenuated material is led up from its source of supply (not herein shown) and is threaded into the tension-device in the following manner: The operator simply draws it into the crotch 125

between the divergent ends of the arms 34 and 44, see Fig. 2, while carrying the end forwardly to the winding machine. When the machine is started to operate the strand y will be caused to draw across the edge of the inclined arm 34 in such manner as to direct it downwardly therewith and into the threadway 29. At the same time, the strand will follow along the curved arm 44 to carry it beneath the bottom edge of the horizontal rim 37 of the member 36 to bring it into alignment with the contacting faces of the tension-disks 20 and 21 whereby to lead the strand into place between said disks as indicated in Figs. 1 and 2 of the drawings. It is to be understood that as the strand y is drawn forward to the traverse-guide 4 and placed in the slot 6 thereof its end is attached to the winding-mandrel 2. In this way as the winding operation is started the strand y will feed forward and be drawn in under the rim 37 and the rearward portion of the arm 45 to direct it between the tension-disks and also between the opposed edges of the slug-catcher blades 50 and 51, the ends of these blades being beveled to provide a V-shaped entrance to the slit or opening therebetween. The strand is thus automatically threaded into proper position in the tension-device and slug-catcher, the operator being only required to lay it across the guide-members 34 and 44.

When it is desired to gain access to the tension-device, either to clean the lint from the operating parts or to add to or subtract from the number of weights on the weight-holder 23, or, in fact, for any other purpose, the main thread-guide member 36 is swung back on its pivot 39 in the manner as illustrated in Fig. 5. This removes the finger 41 from the top of the spindle 16 so that the hood or shroud 28 may be lifted off therefrom to expose the tension-disks and their pressure means comprising the holder 23, weights 22 and spring 25. The parts of the tension-device are thus rendered convenient of access for adjustment or cleaning.

It is to be noted that the tension-disks 20 and 21 are adequately protected from the accumulation of lint or dust particles due to the fact of their being covered over at the top by the hood or shroud 28, while the lower disk 21 is protected from the bottom by the shield or guard 18. Lint, dirt and dust are prevented from clogging the bearings of the disks on the spindle or pin 16 or the action of the sliding weight-holder 23 so that these parts are maintained in proper working order over a long period of time without requiring cleaning. Moreover, it is to be noted that the shelf or base 15 which forms the main support for the tension-device is cut away at 59, see Fig. 2, so that it presents no extended surface to collect lint or dust under the tension-disks. That is to say,

any lint issuing from between the tension-disks as the yarn draws therethrough will drop down clear of the device without lodging in position to obstruct or interfere with the proper functioning of the device. 70

When the strand-guiding member 36 is swung over into the position illustrated in Fig. 5 the slug-catcher is carried up into position to expose the slot or opening between the blades 50, 51 so that the latter may be more readily cleaned of any lint or dust particles which may have become lodged therein. This convenience of access to the slug-catcher thus provides for more thorough cleaning to insure the proper operation of 80 this part of the device.

It will be observed from the above that my invention provides a particularly efficient tension-device in which the tension-members are shielded to protect them from becoming clogged with lint or dust. Another feature of the improvement resides in the means for automatically threading the strand of yarn or other filament into the device. This guiding means insures the proper threading of 90 the strand into place without care or attention on the part of the operator and guards against improper threading. Furthermore, the provision for folding back or removing the strand-guiding means from operative 95 position permits freer access to the tension-mechanism to facilitate the cleaning of these parts and the slug-catcher.

While I have herein described and illustrated a preferred embodiment of the improved device it is to be understood that various modifications may be made in the structure and arrangement of its parts without departing from the spirit or scope of 100 the invention. 105

Therefore, without limiting myself in this respect, I claim:

1. In a tension-device, the combination of 110 tension-means adapted to bear upon a strand of yarn or other filament to apply resistance to its draft, a hood enclosing said tension-means, and guiding-means extending circumferentially of the rim of the hood to adapt it to guide the strand into position to draw through the tension-means, said 115 guiding-means adapted to be moved out of operative position to give free access to the tension-means.

2. In a tension-device, the combination of 120 a pair of tension-elements adapted to bear on a running yarn or other filament to apply resistance to its draft, and a strand-guiding device normally arranged in position partly surrounding the tension-elements to direct the strand into place therebetween and 125 mounted free to be shifted out of position to give access to the tension-elements.

3. In a tension-device, the combination of 130 means for applying tension to a running strand of yarn or other filament drawing

therethrough, and a guiding-device pivotally mounted adjacent the tension-means and extending circumferentially thereof to adapt it to normally assume a position to direct 5 the strand into place therein while being free to swing out of position to give access to the tension-means.

4. In a tension-device, the combination of 10 a pair of tension-elements, means for applying pressure to the tension-elements to cause them to bear against a running strand of 15 yarn or other filament to apply resistance to its draft, a strand-guide arranged adjacent the tension-elements partly surrounding the latter to adapt it to direct the strand into place therebetween, and means for hingedly mounting said guide to adapt it to be swung away from the tension-elements to give 20 access thereto.

5. In a tension-device, the combination of 25 a bracket, a spindle supported from said bracket, a saucer-shaped lint-guard at the bottom of the spindle, a pair of tension-disks mounted on the spindle above the lint-guard 30 with their peripheries overhanging the rim thereof, means for applying pressure to the tension-disks to cause them to resist the draft of the strand passing therebetween, and a hood enclosing the pressure-means 35 and surrounding the rim of the upper tension-disk.

6. In a tension-device, the combination of 40 a bracket provided with a shelf, a spindle projecting upwardly from said shelf, tension-disks mounted on said spindle, a fixed strand-guide extending upwardly from the shelf, and a movable strand-guide adapted to be held in position in spaced relation with the top of the shelf and having a portion extending across the fixed guide to form a crotch to direct the strand downwardly into place between the tension-disks.

7. In a tension-device, the combination of 45 a horizontal shelf, a spindle projecting upwardly therefrom, tension-disks mounted on said spindle with their faces in contact in a plane above the shelf, a threadway at the side of the shelf for directing the strand of 50 yarn or other filament between the tension-disks, a guiding-member projecting upwardly from one side of the threadway, and a swinging guiding-member adapted to be moved into position above the shelf and having an arm arranged to project across 55 the first guiding-member whereby it acts to guide the strand downwardly between the members into the threadway and between the tension-disks.

8. In a tension-device, the combination of 60 a horizontal shelf formed with a vertical threadway for a strand of yarn or thread, a spindle projecting upwardly from the shelf, tension-means mounted on said spindle, and a strand-guiding device pivotally mounted 65 adjacent the tension-means and provided

with a circular rim extending circumferentially thereof and an arm projecting upwardly therefrom whereby to adapt it to lead the strand downwardly to direct it through the threadway and into position in 70 the tension-means.

9. In a tension-device, the combination of 75 a bracket, a spindle supported therefrom, tension-means carried on said spindle, a swinging guide hinged at the side of said tension-means, said guide provided with a circular rim adapted to be set in position surrounding the tension-device and having a curved arm reaching upwardly therefrom in 80 position to direct the strand into the tension-device, and a slug-catcher carried by the swinging guide and provided with a slot through which the strand draws as it leads beneath the circular rim thereof.

10. In a tension-device, the combination of 85 a bracket, a spindle supported from said bracket, tension-disks mounted on said spindle to adapt them to bear against a strand of yarn or other filament drawing 90 therebetween, a guiding-member pivoted to 95 the bracket and having a circular rim adapted to be moved into position surrounding the tension-device, and a pair of blades carried by said guiding-device with their edges arranged in spaced relation substantially in alinement with the under side of the circular rim of the guiding-device.

11. In a tension-device, the combination of 100 upper and lower tension-disks adapted to bear against a strand drawing therebetween to apply tension thereto, and a saucer-shaped 105 lint-guard supported beneath the lower tension-disk with its rim arranged in close proximity to the under side of said disk.

12. In a tension-device, the combination 110 of a spindle, a pair of concavo-convex tension-disks mounted on the spindle with their convex faces adapted to bear on the strand drawing therebetween, and a saucer-shaped 115 lint-guard supported beneath the lower tension-disk with its rim projecting upwardly within the downturned rim thereof to shield the bearings of the disks from lint and dirt.

13. In a tension-device, the combination 120 of a support, a pin projecting from said support a tension-disk mounted on the pin to adapt it to bear against a strand of yarn drawing through the device, a hood supported from the pin and enclosing the 125 tension-disk, and a guiding-member pivoted to the support and provided with a circular portion extending circumferentially of the hood and spaced away from the rim thereof to adapt it to guide the yarn into position to draw across the tension-disk.

In testimony whereof I hereunto affix my signature.

ERNEST ROBERT SWANSON.
